UNITED STATES PATENT OFFICE.

VERNON C. TASKER, OF BRIDGEPORT, CONNECTICUT, ASSIGNOR TO THE AMERICAN ORDNANCE COMPANY, OF NORFOLK, VIRGINIA, A CORPORATION OF VIRGINIA.

AUXILIARY BARREL FOR BREECH-LOADING GUNS.

SPECIFICATION forming part of Letters Patent No. 757,790, dated April 19, 1904.

Application filed June 21, 1902. Serial No. 112,678. (No model.)

To all whom it may concern:

Be it known that I, VERNON C. TASKER, a citizen of the United States, residing at Bridgeport, in the county of Fairfield and State of Connecticut, have invented certain new and useful Improvements in Auxiliary Barrels for Breech-Loading Guns; and I do hereby declare the following to be a full, clear, and exact description of the invention, such as will enable others skilled in the art to which it appertains to make and use the same.

This invention relates to auxiliary barrels for breech-loading guns or, as they are usually termed, "subcaliber devices;" and it consists in the construction hereinafter pointed out and claimed.

In the annexed drawings, Figure 1 represents a longitudinal section of the device applied in place within the powder-chamber of a breech-loading gun to which the invention is to be adapted, only so much of the gun being shown as is necessary to understand the present invention. Figs. 2, 3, and 4, Sheet 2, represent, respectively, a rear elevation and a vertical section of the rear adapter and views of the tongue or plate fitted in the periphery of the adapter. Figs. 5 and 6 represent face and sectional views of the front adapter. Figs. 7 and 8 represent face and sectional views of the middle support. Fig. 9, Sheet 1, represents an enlarged view looking down upon the periphery of the rear adapter where it is separated, showing the tongue or plate in place and the wedge and screw. Fig. 10 represents the screw for actuating the wedge; Fig. 11, two views of the wedge—a top and end view. Fig. 12 represents an end and sectional view of the breech of the subcaliber gun.

In the drawings the letter A indicates the auxiliary - barrel or subcaliber gun, which may be built up in the usual way, consisting of the tube a , the jacket a' , and the breech-hoop a'' . This barrel A is provided on its exterior surface with three sets of screw-threads a^3 , a^4 , and a^5 , all being of the same pitch and direction.

Secured upon the threads a^3 is the front adapter B, upon the threads a^4 the middle sup-

port C, and upon the threads a^5 the rear adapter D, the two adapters and middle support being threaded interiorly to engage the threads upon the surface of the barrel A and also bored to fit the smooth surfaces adjacent to such threads, the more accurately to center the subcaliber barrel. The front adapter B consists of a peripheral ring b and a central hub b' , connected by radial arms b'' . The ring b has its outer face or surface b^3 tapering, so as to be fitted to the inner tapered surface of the large gun beyond the powder-chamber. The hub b' is interiorly threaded at b^6 and has at one end the smooth bore b^6 .

Secured upon the threads a^4 is the middle support C, which consists of the four radial arms c , extending from the central hub c' . The bore of this central hub c' has a threaded portion c^2 and a smooth portion c^3 . The extreme ends c^5 of the radial arms c are curved to fit the inner surface of the powder-chamber of the large gun. This middle support C is not essential to the device, but is provided to additionally insure alinement already sufficiently insured for all practical purposes in most cases by the adapters B and D. The front adapter B may preferably be located upon the middle threads a^4 in cases where the front slope M^2 of the powder-chamber M is farther to the rear than as is shown in Fig. 1. In such cases the support C, if used, is located upon the front threads a^5 .

Secured upon the threads a^5 is the rear adapter D, which constitutes a means of securing the auxiliary barrel in place and adapting it to the inside of the large gun. This adapter consists of a peripheral ring d and a central hub d' . The boss and ring are connected by radial arms d'' , which, however, connect the two only about half-way around the peripheral ring d . That portion of the peripheral ring d away from the radial arms d'' is cut transversely, as shown at d^3 , forming two branches d^4 d^5 , and in the face of the two branches is made a mortise d^6 . In this mortise is placed the tenon or plate d^7 , which is held in place by the rivets d^8 passing through one of the branches and through the plate.

In one branch d^4 is made a transverse threaded hole d^{10} , in which engages the screw E, having the head e, the collar e', and the neck e'' between the head and the collar. The abutting 5 ends of the branches d^4 and d^5 are provided with transverse grooves d^{11} and d^{12} , the former being in the same branch, d^4 , as the screw E is shallower than the other, d^{12} , which is in the other branch, d^5 . Engaging the neck e'' of the 10 screw E are the forks f' of the head f of a wedge F, whose wedged end f'' extends between the meeting ends of the branches d^4 and d^5 and rests in the transverse grooves d^{11} and d^{12} , the slanting or wedged face f''' resting 15 within the groove d^{12} of the branch d^5 . The central hub d' of the rear adapter D is internally threaded at d^{14} and has at one end the smooth bore d^{15} . At one side, preferably that which is away from the branched portion 20 of the periphery d, the central hub d' is provided with a depending lug d^{17} , passing up through which is a slot d^{18} , which penetrates up into the body of the boss, forming a spring-lip d^{19} , through the bottom of which is a passage d^{20} , which may be smooth, alining with the threaded hole d^{21} in the main part of the 25 depending lug d^{17} . A screw G passes through the passage d^{20} and engages the threaded hole d^{21} .

30 The two adapters and the middle support, constructed as described, are put in place upon the auxiliary-barrel or subcaliber gun, the smooth portions of the gun resting in the smooth portions of the adapters and support 35 and the threaded portions engaging. As shown in the drawings, Fig. 1, when in place spaces are left between the threaded portions of the subcaliber gun and the shoulder on the inside of the adapters and support, so as to permit 40 of adjustment.

For any given caliber of gun with which 45 the device is to be used the front adapter and the middle support, which are not radially adjustable, are of a size to snugly fit those portions of the bore of the gun against which they are to bear, the surface of the front adapter being tapered to fit the bore of the gun beyond the powder-chamber and the middle support being adapted to fit the cylindrical interior surface of the gun in the powder-chamber. The rear adapter is also adapted to fit 50 the interior surface of the gun in the powder-chamber; but, as is evident from its construction, there is sufficient mobility of its parts 55 that it may be readily adjusted so as to firmly bear against the interior of the gun, the surface of this rear adapter being cylindrical to fit the interior of the gun.

The auxiliary-barrel or subcaliber gun, with 60 the two adapters and middle support attached to it, is inserted in place from the rear within the breech-loading gun with which it is to be used. The front adapter comes to a bearing just beyond the powder-chamber, the middle 65 support within the powder-chamber toward the

front, and the rear adapter near the rear end of the powder-chamber. In this position the screw E is turned, forcing the wedge F down into the transverse grooves d^{11} d^{12} , forcing the branches d^4 and d^5 apart, they being held in 70 alinement by the tongue or plate d''. These branches d^4 d^5 are forced apart until the rear adapter D is caused to bind with sufficient force against the gun to hold the auxiliary barrel from accidentally moving to the rear. 75 The auxiliary-barrel or subcaliber gun is then to be positioned longitudinally until it is in proper place and properly spaced from the face of the mushroom of the gas-check, when the large gun is closed. This is accomplished 80 by rotating the subcaliber gun, its threads thereupon causing it to move longitudinally. As soon as this position is obtained the auxiliary-barrel or subcaliber gun is bound in place from further rotation by tightening the 85 screw G, which causes the flexible or spring lip d''' to bind the auxiliary barrel from further rotation. The auxiliary barrel may be rotated by any suitable means, as by a wrench having prongs to enter the sockets a' in its 90 rear face.

Having described my invention, what I claim is—

1. Means for supporting a subcaliber gun in a piece of ordnance, consisting of an adapter or ring having two branches, a wedge and screw, the wedge held to one branch by the screw and bearing against the other branch. 95

2. Means for supporting a subcaliber gun in a piece of ordnance consisting of an adapter 100 or ring having two branches provided with a mortise; a plate resting in said mortise, secured to one branch and loose in the other, a screw and a wedge, the wedge held to one branch by the screw and bearing against the 105 other branch.

3. Means for supporting a subcaliber gun in a piece of ordnance, consisting of the adapter or ring, D, having the two branches, d^4 d^5 , provided with the mortise, d^6 , the plate, d^7 , located in said mortise secured to one branch and loose in the other; the wedge, F, fitting between the meeting ends of the branches; and the screw, E, engaging one branch of the adapter and the wedge. 115

4. Means for supporting a subcaliber gun in a piece of ordnance, consisting of the adapter or ring, D, having the two branches, d^4 d^5 , provided with the mortise, d^6 ; the tenon or plate, d^7 , in such mortise and secured to one branch; the wedge, F, fitting between the meeting ends of the branches; and the screw, E, engaging one branch of the adapter and the wedge. 120

In testimony whereof I affix my signature in 125 presence of two witnesses.

VERNON C. TASKER.
